UNITED STATES PATENT OFFICE.

BERNARD FREEDMAN, OF TRENTON, NEW JERSEY, ASSIGNOR, BY DIRECT AND MESNE ASSIGNMENTS, OF ONE-THIRD TO ABRAHAM CLAUSON AND ONE-THIRD TO SAMUEL MEDOFF, BOTH OF PHILADELPHIA, PENNSYLVANIA.

LIQUID-DISPENSING MACHINE.

Application filed December 31, 1926. Serial No. 158,288.

This invention relates to machines for dispensing liquids and particularly to those comprising coin-controlled mechanisms arranged to deliver measured quantities of 5 beverages.

It is an object of the invention to provide in such a machine coin-started instrumentalities arranged while operating for the requisite time, in response to every coin deposited, to permit the discharge by gravity of a predetermined quantity of beverage.

The invention, moreover, associates and coordinates with the liquid-dispensing instrumentalities means whereby a drinking-5 cup is dispensed and made available to the customer at a place where it receives the discharged beverage.

Further, the actuating mechanism provided by the invention is such that it may 10 be mounted on a door of a compartment of the machine normally housing it, so that, when the door is opened, the mechanism is swung outwardly and rendered easily accessible for overhaul, lubrication, etc.

25 Other improvements in the details and arrangement of parts of such machines are made by the invention, as hereinafter explained.

When considered with the description 30 herein, the characteristics of the invention are apparent from the accompanying drawings, forming part hereof, wherein an embodiment of the invention is disclosed, for purposes of illustration.

35 Although the disclosures herein exemplify what now is considered to be a preferable embodiment of the invention, it is to be understood that it is not the intention to be limited necessarily thereto in interpretation of the claims, as modifications and 40 adaptations within the limits of the claims can be made without departing from the nature of the invention.

45 *Drawings.*

Like reference-characters refer to corresponding parts in the views of the drawings, of which—

Fig. 1 is an elevation of the dispensing

mechanism, certain parts being shown in 50 section;

Fig. 2 is a plan view thereof;

Fig. 3 is a perspective of the coin-mouth and associated parts;

Fig. 4 is a vertical section of the coin-mouth;

Fig. 5 is a circuit diagram;

Fig. 6 is an elevation of the machine, with the casing-walls broken away at places;

Fig. 7 is a section on the line 7—7, Fig. 1; 60

Fig. 8 is an elevation of parts of the cup-dispensing mechanism, some of them being shown in section;

Fig. 9 is a section on the line 9—9, Fig. 1.

65 *Casing and piping.*

The casing of the machine, which is of suitable shape and dimensions to enable it to be located in public places where it is accessible to customers, comprehends a lower 70 compartment 10, for containing part 11 of a cooling system; an intermediate compartment 12 thereabove, for containing the dispensing instrumentalities, and having an outwardly-swingable lockable door 13 formed 75 in its wall with an upper slot 14 and a slot 15 therebelow, and with a lower opening 15', and separated from the lower compartment by a liquid-tight partition 16; and an upper compartment 17, having at its bottom 80 a liquid-tight partition 18 and at its top an openable and lockable cover 19.

Pipes 20 afford communication between the parts of the cooling system in the lower compartment and a drum or the like 21 positioned at the back of the intermediate compartment, and coils 22 in the upper compartment are in communication with the drum.

The upper compartment is of such capacity, and the coils therein are arranged in such 90 manner, that a comparatively large bottle or other container of commercial form, as indicated by 23, such as commonly used for sale and shipment of beverages in wholesale quantities, may be placed therein, with its 95 mouth uppermost, within the confines of the coils. After a container thus is placed in the upper compartment, an intake part

24 of a siphon is lowered into the container through its mouth and connected by a coupling 25 to a pipe 26, which extends downwardly at the back of the machine to the lower part of the intermediate compartment. The pipe 26 has an extension 27, which projects forwardly in the intermediate compartment to a downwardly-deflected discharge end or nozzle 28 located opposite to the lower opening 15' of the door.

The partitions separating the compartments are made of impervious material, such as sheet metal, and they are connected by liquid-tight joints to the casing-walls, to prevent liquid that may leak or be spilled in an upper compartment from reaching and injuring mechanism in a compartment therebelow.

20 Mechanisms for operating the liquid and cup dispensing instrumentalities are supported by frame and other members 29 on the door 13, so that, when the door is opened, they are withdrawn from the intermediate 25 compartment and rendered easily accessible for lubrication, overhaul, adjustment, etc.

Liquid-dispensing mechanism.

Flow of liquid from the beverage-pipe 30 and its discharge from the nozzle 28 are controlled by a valve 30 in the pipe-extension 27. The valve has an upwardly-projecting stem 31. A lever 32, having one end pivotally mounted at 33, is connected in its median 35 portion pivotally at 34 to the upper portion of the valve-stem, and its other end is forked or bifurcated, as shown at 35. The valve normally is held closed by a spring 36 connected to the pipe and to the lever.

40 A substantially vertical shaft 37 is reciprocable in one of the frame members; its lower end portion is disposed in the lever-fork 35, and it has an abutment 38 below and contactable with those forks; and it has an 45 abutment, such as a head 39, at its other end. A collar 40 of an operating device 41 of the centrifugal-governor type is rotatable on the shaft 37 and bears against the head thereof. That device is rotated by a shaft 50 42 having a pinion 43 in mesh with a gear 44 on one end portion of a drive-shaft 45 of an electric motor 46.

A worm 47 on the other end portion of the shaft 45 drives a pinion 48 on a shaft 49, and 55 a worm 50 on the latter shaft drives a pinion 51 on a shaft 52. The shaft 52 has fixed to its upper portion a cam 53 formed with a volute-like periphery that commences at the base of a projection 54 and terminates at 60 the outer end thereof. That shaft extends upwardly through, and carries the cam above, a substantially horizontal supporting-member 55 mounted on frame members. An insulating-block 56 on that member has 65 swingably mounted thereon at 57 an arm 58.

The arm at one side of its pivot carries an insulating-piece 59 on which is a projection 60 held in contact with the cam by a spring 61, and a contact-spring 62 opposite to the projection; and on the other side of its pivot 70 it extends as a finger 63 into a coin-mouth 64 from which a chute 65 leads downwardly to a coin-receptacle 66 in the machine. A contact-strip 67, insulated from the door of the compartment, is disposed opposite to the 75 contact-spring 62 and the finger 63.

Electric current is supplied to the motor from any suitable source, as from a light-circuit plugged in at the back of the machine, and thus connected with conductors 80 68 and 69 through the motor to the arm 58 and with a conductor 70, having a resistance R, connected with the contact-strip 67.

A coin-pusher 71, having a finger 72 protrudable into the coin-mouth, is mounted 85 swingably thereon at 73, and it has an operating member 74 extending through the slot 14 to the exterior of the door, by which the pusher may be lifted and depressed.

Cup-dispensing mechanism.

The shaft 37 has thereon two abutments 75, between which loosely are disposed legs 76 straddling the shaft. The legs are terminals of a lever 77 swingably mounted at 78 on a 95 frame part. The other end of the lever extends into a bifurcated end 79 of a lateral extension 80 of an arm 81 swingably mounted at 82 on a frame part. The free end portion of the arm 81 extends into a bifurcated 100 end 83 of a lever 84, which has at its other end a pawl 85, and also curved legs 86 journaled on an upright shaft 87. An annular rack 88 fast on the shaft between the legs 86 is engageable by the pawl. The shaft is 105 journaled in frame members, and a rotary table 89 is fixed to its lower portion. A wheel 90 (hereinafter referred to as the ratchet-wheel) is fixed on the upper portion of the shaft, and it has peripheral teeth 91 110 with curved surfaces.

A spring 92 interposed between any suitable fixed abutment (as the door of the compartment) and an abutment 93 on a rod 94 keeps an end of that rod in contact with the 115 periphery of the ratchet-wheel. The other end of the rod carries a substantially semi-circular arm 95, which extends around one side of the lowermost one of a stack of cups C, and which has an inwardly-extending terminal stop 96 normally maintained under the rim of that cup by the spring 92, whereby to prevent the cup from dropping. Opposite to the terminal stop 96 there is another stop 97 on the rod (or arm) in a slightly higher 120 plane positioned to be moved under the rim of the cup next above the lowermost and normally maintained out of alignment therewith by the spring 90.

The cups are stored in an upright tube 130

98. That tube is carried by, and leads into, a supply-tube 99, which is mounted on the door, leads into the intermediate compartment, and terminates above the table 89.

5

Operation.

The parts of the dispensing mechanisms are shown by the drawings in their normal or inactive positions. The coin mouth or slot is proportioned to receive a coin no larger than that for which the machine is adjusted.

When a coin, such as M, of the proper value is inserted into the coin-mouth after lifting the coin-pusher 71, it comes into contact with the finger 63 and the contact-strip 67. The pusher by pressing of its finger 72 on the coin reliably maintains that contact. The coin in that position closes the circuit through the conductors 68 and 69 through the motor to the arm 58 and through the conductor 70 connected with the contact-strip 67. The parts are coordinated so that, when they are in their normal positions, only a coin as large as that intended to be received will pause in contact with the finger 63 and contact-strip 67; and, if a smaller coin is inserted, it will drop at once and not momentarily remain in contact with both that finger and strip.

Upon closing of the circuit through the coin, the motor is started, and the cam 53 commences to rotate. The cam, by acting on the projection 60, swings the contact 62 toward the strip 67 and the finger 63 in the opposite direction, and thus permits the coin to drop from between the finger and strip. The parts are coordinated in such manner that the contact 62 reaches the strip 67 at or just before the coin drops and breaks the circuit at that place, and the circuit remains closed through the contact 62 and the strip until the cam-projection 54 passes beyond the arm-projection 60, whereupon the spring 61 returns the arm 58 to its normal position and withdraws the contact 62 from the contact-strip and breaks the circuit and stops the motor. When the motor stops, the valve is closed by recessive action of the centrifugal device and by the spring 36, and by that means also reverse motion is imparted to the lever 84 and pawl 85.

During the period the motor is running, the centrifugal operating device 41, through the instrumentality of the shaft 37, swings the lever 32 and opens the valve 30 and permits liquid to flow from the nozzle 28 into a cup previously deposited on the table 89. The shaft also, in the same period, swings the lever 77 sufficiently to impart a quarter turn to the shaft 87 through the action of arm 81 and the pawl and rack associated therewith. This turn moves the table to bring the cup that just has received liquid

from the nozzle to position just inside of the opening 15' of the door, where it easily may be reached by the customer. During this movement, the ratchet-wheel 90 swings one of its teeth across the end of the rod 94 and thus moves the stop 96 from under the rim 70 of the lowermost cup of the stack and permits it to drop and simultaneously brings the stop 97 momentarily under the rim of the cup that then becomes the lowermost and holds it; and, as the tooth passes from the end of the rod, the spring 92 returns the shaft to its normal position, releases the stop 97 from the cup and brings the stop 96 at once under its rim whereby it is prevented from falling. The released cup is deposited on the table under the nozzle. Reverse movement of the shaft 87 is prevented by contact of rod 94 with the ratchet-wheel.

The parts are coordinated in such manner that the valve remains open during a cycle 85 of operation of the mechanism only long enough to permit flow of a predetermined quantity of beverage, as, for example, enough nearly to fill a cup, and so that the cup then is turned by the table from under the nozzle 90 and another cup permitted to drop to position thereunder as soon as the liquid-containing cup is moved.

When the door is opened, all of the dispensing mechanisms mounted thereon are 95 withdrawn from the compartment, except the valve and its operating-lever, and thus the mechanisms are readily accessible for lubrication, adjustment, and overhaul. Such movement of the parts is permitted, because 100 the lower end of the shaft 37 is withdrawable from the forked end 35 of the valve-operating lever.

What I claim as new, and desire to secure by Letters Patent, is—

105

1. In a liquid-dispensing machine, the combination of a nozzle, a normally-closed valve controlling discharge from said nozzle, a centrifugal device arranged while driven to cause said valve to open, an electric motor for driving said device, a coin-started circuit make-and-break device for said motor, a rotatable table under said nozzle, a cup-holding tube, a guideway from said tube terminating above said table, a 115 shaft connected with said table, a shiftable cup holding and releasing member, an operating device for said member actuated by said shaft, and means whereby said shaft is turned by said centrifugal device.

120

2. In a liquid-dispensing machine, the combination of an outwardly-swingable door of a compartment thereof, a normally-closed valve in the compartment controlling discharge of liquid, an operating member for said valve, and the following instrumentalities mounted on said door: a centrifugal device slidingly connectable and disconnect-

125

able with said operating member during closing and opening movement of said door, an electric motor for driving said device, and a coin-started circuit make-and-break device for said motor.

3. In a liquid-dispensing machine, the combination of an outwardly-swingable door for a compartment thereof, a normally-closed valve in the compartment controlling discharge of liquid, an operating member for said valve, and the following instrumentalities mounted on said door: a cup-dispensing mechanism, a centrifugal device slidably connectable and disconnectable with said operating member during the closing and opening movement of said door and arranged while driven to open said valve and actuate said mechanism, an electric motor for driving said device, and a coin-

started circuit make-and-break device for 20 said motor.

4. In a liquid-dispensing machine, the combination of an outwardly-swingable door for a compartment thereof, a normally-closed valve in the compartment controlling 25 discharge of liquid, an operating member for said valve, and the following instrumentalities mounted on said door: a reciprocable shaft sliding connectable and disconnectable with said operating member during closing 30 and opening movement of said door, a centrifugal device arranged to move said shaft, an electric motor for driving said device, and a coin-started circuit make-and-break device for said motor.

In testimony whereof I affix my signature.

BERNARD FREEDMAN.
